UNITED STATES PATENT OFFICE.

MARTIN SVALLAND, OF NEW YORK, N. Y.

RAIL CROSSING.

Application filed June 18, 1921. Serial No. 478,523.

To all whom it may concern:

Be it known that I, MARTIN SVALLAND, a citizen of the United States, residing at New York city, borough of Manhattan, in the county and State of New York, have invented a certain new and useful Rail Crossing, of which the following is a specification.

This invention is a rail crossing intended especially for street railways, although 10 adapted for general use on railroads as well.

It is a well known fact that at rail crossings during the passing of car wheels over the rail intersections, there is a momentary interval during which the wheel of the car 15 is unsupported by the rail head. This interval corresponds to the time when the wheel is passing over the gutter of the rail extending in angular relation to the rail on which the wheel is traveling. During this 20 interval, the wheel drops into the gutter of the angularly disposed rail and immediately thereafter climbs out of the opposite side thereof and proceeds along its way. When a car is rapidly moving along the track over 25 a crossing, the passage of the wheels across the transverse gutters causes the wheels to momentarily leave the rails, due to their sharp impact with the transverse gutters, and when the wheels again engage the rails, 30 they do so with a relatively hard knock, which, in practice, has been found to effect excessive wear on the tracks adjacent the transverse gutters, as well as produce fractioning of the material of such rails at the 35 cross-over. In time, the rails become so badly worn at the cross-over that the rail intersections, either become broken or so noisy as to be objectionable to residents in the locality and must thereupon be replaced. 40 Furthermore, the pounding of wheels due to the sharp knocks referred to effects a crystallization of the material from which the cross-overs are constructed, thereby rendering the same liable to breakage at any 45 time.

In accordance with the present invention, the foregoing disadvantages are obviated through the provision of means associated with each rail intersection for positively 50 supporting a wheel during its passage over the transverse gutter. Various expedients have heretofore been suggested for accomplishing this general result, but they are, in the main, so expensive to install as to 55 render their use prohibitive. Moreover, they

are of a bulky, cumbersome nature, which requires considerable space beneath the cross-over, thereby necessitating the construction of a masonry foundation with arches and other engineering expedients to support the rail at the cross-over and still leave beneath such cross-over sufficient space for the housing of the operating means. Furthermore, many of the prior devices are controlled electrically. 60

The object of the present invention is to positively support wheels at the cross-over in a purely mechanical manner and by mechanism extremely simple and effective in its operation. Moreover, to so constitute such 65 means that the supporting means at each rail intersection will be individually controlled; that is to say, that the supporting means at each rail intersection will be controlled by a car wheel approaching on the 70 associated track entirely independently of the control of the supporting means at the other rail intersections of the cross-over.

In a conventional double track cross-over, where, for example, two tracks running 75 north and south are intersected by two other tracks, running east and west, there are formed 16 rail intersections, which, in accordance with the present invention are individually controlled and no one of which 80 is dependent for its operation upon any of the others. By this arrangement, I am able to attain unusual simplicity in construction and compactness of the operating parts and can furthermore place the controlling means 85 so close to the actual intersection that the intersection is guarded by the overhang of the car before the controlling means is operated to prepare the rail cross-over for the 90 passage of the forward wheels of the car 95 thereover.

Features of the invention, other than those specified, will be apparent from the herein-after detailed description and claims, when 100 read in conjunction with the accompanying drawings.

The accompanying drawings illustrate different practical embodiments of the invention, but the constructions therein shown are to be understood as illustrative, only, 105 and not as defining the limits of the invention.

Figure 1 shows a rail intersection in which the present invention is associated, said rail intersection being shown in phantom in or- 110

der that the operating parts associated therewith may be more clearly seen.

Figure 2 is a front elevation of the construction shown in Figure 1.

5 Figure 3 is a bottom plan view of the same; and,

10 Figure 4 is a perspective view of the modified form of lifting member which may be employed in lieu of the one shown in Figure 1.

15 Referring to the drawings, 5 designates a rail section extending, for example, in a north and south direction, and 6 designates an intersecting rail section extending in an east and west direction. These rail sections are formed en-bloc in the usual manner as by forging or welding and are suitably reinforced by webs or fillets, so as to give a rigid construction at the intersection. The 20 rail sections 5 and 6 are provided with gutters 5^a and 6^a, which extend in angular relation to one another and intersect at the center of the plug, and the outer ends of each of the rail sections 5 and 6 are shaped to 25 conform to rails adapted to be positioned in end abutting relation thereto and secured in position by fish plates and bolts passing through bolt holes 5^b and 6^b formed in the webs of the rail sections, as clearly shown 30 in Figures 1 and 4. A wheel passing along a rail associated, for example, with the rail section 5 will, in passing the cross-over traverse the inner side of the gutter 5^a, across the intersection gutter 6^a and pass off of the 35 cross-over and leave the same through the other section of the cross-over.

40 In associating the present invention with a cross-over of the character specified, I employ two supporting plungers 7 and 8. These plungers may be of any desired construction, but are preferably rectangular in cross section and of a width substantially equal to the width of the gutters 5^a and 6^a. The two plungers 7 and 8 are mounted for 45 vertical reciprocation in vertical holes or guide ways extending through the intersection block and are made flat at their upper ends. When in elevated positions, the upper ends of the plungers 7 and 8 are adapted 50 to come flush with the upper face of the cross-over block, while in depressed positions, they are adapted to come flush with the base of the gutters.

55 The plungers are positioned directly adjacent the intersection of the gutters 5^a and 6^a and the holes in which they operate extend downwardly from the bases of said gutters. These plungers are operated alternately in opposite directions by a web or 60 cam member of any suitable construction organized to raise one plunger and simultaneously permit of the depression of the other and vice versa, and for the purpose of illustration, I have shown two forms of 65 wedge or cam member which may be utilized

for this purpose. In Figures 1-3, this member, which may be broadly designated an operating member, bears the reference character 9, and in Figure 4, the modified form of operating member is designated by 70 the same reference character. The operating member 9, as shown in Figure 1, is in the form of a plate secured for oscillation on a vertical spindle 10. A segmental portion of the plate 9 is cut away and along 75 the bordering radii of the cut away portion the plate is bevelled as at 7^a and 8^a, so as to form two opposed wedges. The spindle 10 is so disposed as to position the operating member to control the operations of both of the plungers 7 and 8, so that when the parts are in the position shown in Figure 1, the plunger 8 will be in lowered position and its lower end will occupy the cut away portion of the operating plate, while the plunger 7 will rest on top of the operating plate. If the spindle 10 is rotated in a counterclockwise direction, its rotation will effect a travel of the operating plate so that the wedge 8^a will ride under the 80 plunger 8 and cause the plunger 8 to be elevated, while the wedge 7^a will back off from under the plunger 7 and allow the said plunger to fall by gravity into its depressed position. It will thus appear that through 85 the oscillation of the spindle 10, alternately in opposite directions, the operating plate may be caused to raise the plunger 7 and depress the plunger 8 and vice versa. When 90 the plunger 7 is raised, the face of a wheel passing through the channel 6^a will ride over the upper end of the plunger 7, while the plunger 8 will be withdrawn out of the 95 path of the flange of the wheel and when the wheel passes through the gutter 5^a, the plunger 7 will be retracted, while the face of the wheel will engage with the upper 100 end of the plunger 8 during the passage of such wheel over the gutter 6^a.

105 In order that the weight imposed on the wheels may be properly supported by the plungers 7 and 8, the operating member 9 is supported from underneath by a firm and rigid member 11, which may either be bolted to the intersection block or may be formed integral therewith. The operating member seats on the top of the supporting member and the weight transmitted to the operating member is carried directly by the supporting member, so that bending of the operating member will not occur.

115 It is essential for the proper operation of the cross-over that the positions of the plungers be accurately-controlled so that 120 they will be in proper position for an approaching wheel.

125 In the preferred form of this invention, the positions of the plungers 7 and 8 are controlled by two controlling members 12 and 14. These two members may be of any 130

suitable shape, but are shown in the form of plungers, mounted for vertical reciprocation in the bases of the gutters 5^a and 6^a at relatively short distances from the supporting plungers 7 and 8, respectively. These controlling plungers are moreover so connected with the supporting plungers 7 and 8, that when a wheel flange engages with the plunger 12, it will raise the plunger 8, and depress the plunger 7 and when a wheel flange engages the plunger 14, it will depress the plunger 14 and the plunger 8 and simultaneously raise the plunger 7. The connections between the plungers 12 and 14 and the operating member 9, which controls the movements of the plungers 7 and 8 may vary without departing from this invention, but for the purpose of illustration, I have shown these parts connected by links and levers. Thus the controlling plunger 12 is provided with an aperture 15 into which projects one arm of a bell crank 16. The bell crank arm 16 is mounted for oscillation on a pivot 17 and the depending arm of the bell crank is pivotally secured to a link 18. The other end of the link 18 is pivoted to an arm 19 formed rigid with the spindle 10.

In like manner, the plunger 14 is apertured at 20 to receive one arm of a bell crank 21 pivoted at 22 and to the other arm of which is pivoted a link 23. The other end of the link 23 is pivoted to an arm 24 rigid with the spindle 10. When a flange of a wheel passing along the gutter 5^a engages the plunger 12, it will depress its plunger, and oscillate the bell crank 16. This movement of the bell crank will be transmitted through the link 18 to the arm 19 and cause rotation of the spindle 10 to move the operating plate from beneath the plunger 7 and allow the same to descend and simultaneously cause the wedge 8^a to lift the plunger 8, so that by the time the wheel has reached the gutter 6^a, it will find ample support on the upper end of the supporting plunger 8. A wheel passing along the gutter 6^a will effect a similar operation on the controlling plunger 14 to the end that the plunger 8 will be lowered and the plunger 7 elevated.

In carrying out this invention, the arrangement of the character described is associated with each rail intersection, so that each intersection is individually and locally controlled in a manner entirely independent from all of the other rail intersections of the group. It has not been considered necessary to illustrate a group of four or sixteen intersections as a mere duplication is embodied in the construction.

It has not been considered necessary moreover to detail the intersection block as the block may differ in construction. In the drawings, the spindle 10 is shown as

projecting downwardly below the block and journaled at its lower end in a depending yoke 25. It will be understood, however, that instead of positioning the links 18 and 23 and the arms 19 and 24 below the block, 70 the block may be slightly deeper and the levers housed directly therein. In practice, moreover, the operating adjuncts described as below the block may be housed within a metal casing or otherwise and may be kept flooded in oil or other lubricant to assure their proper operation, although, in practice, this is not essential. The drawings illustrate the links and levers as pivotally connected through hinge pins, but, in practice, these connections may be in the form of ball and socket joints or any other form of joints which I may prefer to employ. The upper ends of the controlling plungers 12 and 14 are shown with upper rounded ends, 75 but, if desired, they may be formed with a tapering lead so that they will be more slowly engaged and evenly operated by the flange of an on-coming wheel.

It will be apparent that the operating plate shown in Figure 4 will function in the same manner as the operating plate shown in Figures 1-3, the differences being purely constructional, but the device of Figure 4 being stronger and more durable in construction than that of Figures 1-3. In the accompanying drawings, the plungers 7 and 8 are shown as controlled from only one direction, yet it will be understood that by duplicating the control construction on the other side of the intersection, these plungers may be controlled from both directions.

It will be apparent from the foregoing description that the present invention contemplates an individual local control for each rail intersection and that such control is of a positive mechanical character, compact in form, and simple in construction. The structure is moreover one which after being set will carry the weight imposed at the cross-over without imposing undue strains on any of the operating mechanism. The plungers are merely brought into supporting position and are thereafter backed up by a firm metal foundation so that the operating mechanism does not have to carry any strain whatsoever. This construction is such as to minimize wear and obviate breakage.

I am aware that various changes in mechanical detail may be made in the present invention without departing from the spirit thereof and the same is to be understood as broadly novel as is commensurate with the appended claims.

Having thus fully described the invention, what I claim as new and desire to secure by Letters Patent is:

1. A rail crossover, embodying two intersecting rails, each of which is provided with 130

a gap to permit the passage of the flange of a wheel on the other, a wheel supporting member for bridging each gap, a rotary operating member adapted to move one supporting member into supporting position and to simultaneously permit the retraction of the other supporting member, and controlling means associated with each rail for rotating the operating member, said operating member being constituted to remain in the position it is placed by the controlling means of one rail until it is positively rotated to another position by the controlling means of the other rail.

2. A rail cross-over embodying a body portion provided with intersecting gutters, a wheel supporting element associated with each gutter adjacent the intersection thereof, a rotary operating member common to both supporting members for simultaneously moving one supporting member into supporting position and permitting the other to move out of supporting position, a controlling member associated with each gutter, at a distance from the intersection of the gutters, and operative connections between both controlling members and the operating member, whereby the operation of said supporting members may be effected by a wheel traversing either gutter and rendered operative to allow the wheel to pass the intersection and be supported during such passage.

3. A rail cross-over embodying a body portion provided with intersecting gutters, a wheel supporting plunger mounted for reciprocation through the base of each gutter adjacent the intersection thereof, a rotary operating member common to both plungers for simultaneously moving one supporting member into supporting position and permitting the other to move out of supporting position, a controlling member associated with each gutter, at a distance from the intersection of the gutters, and operative connections between both controlling members and the operating member, whereby the operation of said supporting members may be effected by a wheel traversing either gutter and rendered operative to allow the wheel to pass the intersection and be supported during such passage.

4. A rail cross-over embodying a body portion provided with intersecting gutters, a wheel supporting plunger mounted for reciprocation through the base of each gutter adjacent the intersection thereof, a rotary operating member common to both plungers and adapted when operated to lift one of them into wheel supporting position and to simultaneously permit the dropping of the other to allow a wheel flange to pass, a controlling member associated with each gutter and adapted to be actuated by an on-

coming wheel, and operative connections between both controlling members and the common operating member.

5. A track crossover, embodying four intersecting rails, a pair of supporting plungers associated with each rail intersection, a common operating member for operating each pair of supporting plungers, each operating member being separate and independent of the operating members of the other intersections and being individually controlled, and means associated with both rails at each intersection, and separate from the operating members, for controlling the associated operating members, each operating member being constituted to remain in the position it is placed by the controlling means of one rail, until it is positively shifted by the controlling means of the associated intersecting rail.

6. A rail cross-over embodying a wheel supporting plunger associated with each rail adjacent the gap of the intersection, a rotary plunger operating member common to both plungers, and mechanical controlling means operable by an approaching wheel for actuating the common operating member to move the plunger of the rail on which the wheel is moving into wheel supporting position and to simultaneously permit the plunger of the transverse rail to move into non-supporting position.

7. A track crossover, embodying four intersecting rails, a wheel supporting member associated with each rail, at each intersection, a rotary operating member for operating the two supporting members at each rail intersection, and means, operable by a moving car, for actuating each of the rotary operating members, individually and independently of all the other operating members.

8. A rail crossover, embodying a pair of intersecting rails, a supporting member associated with each rail, for bridging the gap at the crossover of such rails at the intersection, a rotary wedgelike member associated with the intersecting rails and serving as a common operating means for both supporting members, and means associated with each rail, and operable by an approaching wheel, for controlling the positions of the wedgelike member to move one of the supporting members into position to support an oncoming wheel and to simultaneously permit the other supporting member to move out of the path of the flange of said wheel.

9. In a rail crossover, a body portion embodying intersecting gutters adapted to be traversed by wheel flanges, a wheel supporting plunger operating through the gap of each gutter, adjacent the intersection of said gutters, a cam member cooperable with the lower ends of the plungers and adapted to elevate one plunger into position wherein

its upper end will be flush with the upper face of the body portion and simultaneously permit the other plunger to descend so that its upper end will be retracted from the gutter in which it is positioned, a controlling plunger associated with each gutter at a distance from the intersection, and operative connections between the controlling plungers and the cam member whereby the

depression of one of the controlling plungers 10 will effect a depression of the supporting plunger in the same gutter, and simultaneously elevate the controlling plunger and supporting plunger of the other gutter and vice versa. 15

In testimony whereof I have signed the foregoing specification.

MARTIN SVALLAND.
